UNITED STATES PATENT OFFICE.

WILLIAM A. LACKE, OF CHICAGO, ILLINOIS.

MOTOR-CONTROLLER.

No. 833,228.

Specification of Letters Patent.

Patented Oct. 16, 1906.

Application filed November 29, 1905. Serial No. 289,661.

To all whom it may concern:

Be it known that I, WILLIAM A. LACKE, a citizen of the United States, residing at 177 Ninety-first street, Chicago, in the county of

5 Cook and State of Illinois, have invented certain new and useful Improvements in Motor-Controllers, of which the following is a specification.

This invention relates to that class of electric motor starters and controllers which embody means for cutting out the starting resistance from the armature-circuit and so arranged as to allow the armature to speed up sufficiently to absorb the inrush current without liability of overload.

The object of my invention is to provide a hand-operated motor starter or controller of this general character embodying a novel arrangement and construction of the parts, 20 whereby a succession of solenoids will automatically control and cut out all the starting resistance step by step, so that no matter how carelessly the operator may manipulate the starting and reversing switches the inrush current to the armature of the motor will be automatically governed and whereby the full force of the inrush current will be included in the armature-circuit only after an appreciable time shall have elapsed to allow 25 the armature to speed sufficiently to absorb the inrush current, thereby preventing an overload and its consequent disadvantages and injurious results.

For a full description of the invention and 35 the merits thereof and also to acquire a knowledge of the details of construction of the means for effecting the result reference is to be had to the following description and accompanying drawings, in which—

40 Figure 1 is a sectional and side elevation of the improvements comprising my invention, the view being taken from what might be generally considered the front side of the switch and parts being shown somewhat in the nature of diagrams. Fig. 2 is a diagrammatic view illustrating all of the circuits included in one embodiment of the invention. Fig. 3 is an approximately similar view illustrating the reverse side of the starting and reversing switch of my invention. Figs. 4 and 45 5 are transverse sections through the switch-handle and segment that is attached thereto and that carries the brushes for effecting the closing and opening of the various circuits, the sections being taken on the lines X X and Y Y, respectively.

Corresponding and like parts are referred to in the following description and indicated in all the views of the drawings by the same reference characters.

In the present instance the starting and reversing switch is mounted within the oil-tank 1, which is provided with a cover 2, to which the main portion of the tank is detachably connected, as by clamping-screws 3, so that 45 the tank may be let down from its cover whenever desired to inspect the interior parts, such downward movement being preferably limited by a chain 4, connected to the top of the tank and its cover, respectively, so 50 that the tank may be suspended in position for such inspection. The switch 5 comprises a preferably segmental plate 6, integrally connected with the actuating-handle 7 and pivotally mounted to swing in a vertical 55 plane within the oil-tank on a pivoted stud or the like 8, mounted in the cover 2. The segmental plate 6 of the switch carries a predetermined number of brushes which are in the present instance in the form of sliding contact-plates, said brushes being arranged, preferably, in two sets on opposite sides of a plurality of terminals or contact-plates for the purposes of closing and opening the various circuits hereinafter specifically described. 60 In the present instance the brushes designated 9 and 10 and 11 and 12 are for the purpose of closing and opening the main-line circuits and for the purpose of reversing the current in the armature-circuit, and on the segmental plate 6 there are complementary brushes designated 9^a, 10^a, 11^a, and 12^a, respectively, on the opposite side thereof, as best seen in Fig. 3. As illustrated in the diagrammatic view the brushes 9 and 9^a are 65 electrically connected, as are the brushes 10 and 10^a. From this description it is evident that the brushes 9 to 10^a, inclusive, are for the purpose of closing the circuit of the motor to actuate the same in a forward direction, and that the other brushes are for the purpose of reversing the motor, according to the direction in which the handle 7 is turned. The brushes designed to successively cut out the various steps of the resistance in the armature-circuit are mounted on either side of the terminals in a stepped arrangement, as shown, so that they will cut in one after the other, and for the purposes of distinction the 70 are designated, respectively, 13 13^a, and so on, 13^b as will be best seen by reference to Figs. 1 and 4. The terminals or contact-plates for

the various brushes are secured to some stationary support in a desired manner between the two sets of brushes and are here designated A to F, inclusive. The terminals A 5 and B have complementary terminals A' and B', arranged, preferably, in juxtaposition thereto, and the latter terminals are designed for the leads of the armature-circuit and for contact by the brushes 9^a, 10^a, 11^a, 10 and 12^a.

The plate 6 is provided on its outer edge with a section of gear 17, which meshes with a small pinion 18, and the latter is provided with a pin 18^a, connected to a contractile 15 spring 18^b, so as to normally hold it in one position. The pinion 18 is of such size that in moving the switch from one contact-spring to another, or, in other words, from one step to the next, the pinion will revolve once. 20 This will insure the contact being made accurately. It will be understood that the oil-tank, which submerges in oil all of the contacts of the switch, thereby insures the prevention of all injury which would otherwise result from arcing, the oil immediately effecting an extinguishing of all of the arcs, and thereby protecting all of the parts from the injurious blistering which would otherwise ensue.

25 The switch-handle 7 is provided with a roller 19, which in the normal central position of the handle is in operative contact with the arm 20, fulcrumed at 21 on a bracket 22 and carrying at its other end a preferably 30 bronze spring 23, to which a copper contact-block 24 is attached. The spring 25 is secured to the arm 20 and to the cover 2 and tends to draw the arm 20 in a direction to make contact between the block 24 and a 35 similar block 26, and this action of the spring 25 is prevented when the switch-handle 7 is in the central position by means of the roller 19, which holds the arm 20 in such position that the blocks 24 and 26 are 40 out of contact with each other. When the switch-handle is moved in one direction or the other, the pin 19 will be moved off the center and out of engagement with the arm 20 and will thereby permit the spring 25 to act 45 to effect the contact of the blocks 24 and 26; but the action of the spring and the movement of the said arm are retarded by means of an oil-gag or other form of dash-pot 27. The block 26 is in the present instance attached to a preferably bronze spring 26^a, which is secured to an axially-adjustable 50 sleeve 28, so that the block 26 may be held at varying distances from its complementary block 24 to insure the proper contact of the 55 two blocks.

In connection with the hand-operated switch above described my invention embodies a succession of automatic switches in the form of solenoids, each of which is 60 provided with an oil-gag or dash-pot mech-

anism, and each of which in turn governs or controls the next succeeding solenoid in such manner that each solenoid which is connected to a predetermined step in the resistance of the armature-circuit will operate only 70 after the solenoid for the preceding step in the resistance has operated. As shown in Fig. 1, these solenoids are electromagnetic switches comprises in the present embodiment of the invention a solenoid 29, provided with a core 30, carrying at one end an armature 31, designed to bridge terminals F and R, respectively, when the solenoid is energized to lift its core. The other end of the core 30 is connected by a link 32 to one 80 end of a rocking arm 33, fulcrumed at 34 and carrying a roller 35 normally in engagement with an arm 36, similar to the arm 20, and also provided with an actuating-spring, oil-gag, or other dash-pot mechanism, and a 85 contact-block, as shown. With this last-named contact-block (designated 37) there is designed to coat a contact-block 38, which is adjustably mounted, as shown, and is connected to the common return for 90 the current from all of the electromagnetic switches, as will be hereinafter described. In connection with a solenoid 29 and its concomitant parts is a predetermined number of similar solenoids which I have not deemed 95 necessary to illustrate and describe in detail, but will describe their function and operation in connection with the other parts of the mechanism. In the drawings the entire resistance to be cut out from the armature-circuit is designated by legend and the several steps in the resistance are respectively designated R^a, R^b, R^c, and R^d. The field for the motor is also properly designated and illustrated diagrammatically, as 100 105 are also the armature and its leads.

Having described the mechanical features of my invention and such parts of the electrical mechanism which depend upon mechanical devices for actuation, I shall now 110 proceed to describe the various circuits in connection with a description of the operation of the device for cutting out the various steps in the resistance.

In the practical use of my invention if the 115 handle 7 is turned so as to bring the brushes 9 and 10 into contact with the terminals A and B and the brushes 9^a and 10^a simultaneously with the terminals A' and B' the circuit to the motor will be closed with all of the 120 resistance in, and the path of the current would be as follows: from the plus side of the line to the terminal B and brush 10 to brush 10^a to the armature-lead 100, around the armature, and back through the other armature-lead 100^a to the terminal A', thence to the brush 9^a and brush 9, and thence out through the terminal A around the field, and through all of the resistance back to the negative side of the line. When the motor is re- 125 130

versed, the handle 7 is moved in an opposite direction, so as to bring the brushes 11 and 12 into engagement with the terminals A and B and the brushes A' and B'. The path of the current will then be as follows: from the plus side of the line to the terminal B, brush 12, through the switch to brush 11^a, thence to the terminal or contact A' to the armature-lead 100^a, around the armature, back through the armature-lead 100, thence to the brush 12^a, through the switch to the brush 11, and, finally, out through the terminal A around the field of the motor and through all of the resistance back to the negative side of the line. So far I have described circuits with all of the resistance cut in. I shall now trace the path of the current and describe the circuits when the handle 7 is pulled to the right far enough to effect the engagement of one of the resistance cut-out brushes and its proper terminal or contact-plate to effect the cutting out of one step in the resistance. When the handle 7 is pulled over just far enough to allow the brush 13^a to contact with the terminal or contact C, the current will flow from the line and contact-block 24 over the contact-plate C, and, if sufficient time has elapsed to allow the blocks 24 and 26 to come into contact with each other the current will flow to and through the solenoid 29, energizing the latter, and causing the core 30 thereof to pull up the armature 31 therein to bridge the contacts F and R. The path of this shunt-current or electromagnetic switch current will be as follows: from the plus side of the line through the terminal B and brush 12, brush 13^a, terminal C, blocks 24 and 26, solenoid 29, and common return-point 200 for all of the electromagnetic switches, and thence back to the negative side line. The path of the current around the armature with the parts actuated as just described will be from the plus side of the line to the terminal B, brush 12, to the brush 11^a, armature-lead 100^a, around the armature through armature-lead 100, brush 12^a, brush 11, terminal A, through the field to the contact F of the first electromagnetic switch or solenoid 29, through the armature 31 to the other contact R of said solenoid, thence to R^a in the resistance and through the remaining steps of the resistance out to the negative side of the line. By throwing the switch-handle 7 farther over so as to bring the contact D and brush 14^a in contact, the second of the electromagnetic switches will cut in, providing, however, that the make-and-break devices 37 and 38 of the first automatic switch or solenoid shall have had time to make contact and close the circuit, thereby cutting out the resistance-steps R^a and R^b. The path of the operating-current for the switches will then be from the plus side of the line to the terminal B, brush 12, through the connecting-wire 300 and brush

14^a to the terminal D, thence through the second solenoid, which I have designated II in contradistinction to the first solenoid, which is designated I, through the make-and-break devices 37 and 38 of the solenoid I, if 70 the latter and the make-and-break device 24 and 26 shall have had time to successfully close the circuits, and thence to the common return for all of the electromagnetic switches to the negative side of the line. The path of the current through the motor will be from the plus side of the line to the terminal or contact B, through the brush 12, brush 11^a, contact A', armature-lead 100^a, around the armature, back through armature-lead 100 80 to terminal B', to brush 12^a, to brush 11, to terminal A, through the field to the contacts F' and R' of the solenoid II to the step R^b in the resistance, and through said step and the other step R^d to the negative side of the line. 85 It is believed that with this description the various circuits for the other resistance-steps will be clearly comprehended and that further explanation of the circuits is not necessary. 90

It will of course be understood that by moving the switch-handle 7 in the direction opposite to that described in connection with the various circuits the armature-current will be reversed. The operation of the electromagnetic switch, oil-gags, or other dash-pot mechanism and the other parts of the apparatus is the same for either direction of the motor-armature current. 95

From the foregoing description, in connection with the accompanying drawings, it will be seen that I have provided a motor starting and controlling mechanism which embodies a succession of automatic or electromagnetic switches designed to successfully 100 cut out the resistance-steps from the armature-circuit, and are arranged so that the actuation of one depends entirely upon the previous automatic operation of the preceding solenoid or electromagnetic switch, 105 whereby should the attendant throw the switch-handle over carelessly into such a position that without the safeguards that I have provided the motor-armature would receive the full force of the inrush current in 110 a detrimental manner my invention will prevent the immediate short-circuit of the resistance and will automatically, by a step-by-step arrangement, insure a sufficient retardation of the cutting-out operation and 115 will allow the motor to properly absorb the inrush current without becoming overloaded. 120

Having thus described the invention, what is claimed as new is—

1. The combination with a motor-armature circuit and resistance therefor, of a source of supply, a reversing-switch designed to connect the source of supply to the armature-circuit, a series of slow-closing switches each provided with an automatic circuit- 125

- closing device, and the said device of one slow-closing switch being arranged in series with the solenoid controlling the operation of the succeeding switch whereby means are provided for automatically closing the circuits of the various solenoids in succession, each of said solenoids being in shunt to said resistance, and the automatic circuit-closing device for the first solenoid in the series being controlled by the reversing-switch.
2. The combination with a motor-armature circuit, a source of supply therefor and a resistance, of a series of solenoids, a series of slow-closing switches each of which shunts a part of the resistance in the armature-circuit and each of which except the first is controlled by a preceding solenoid, and a reversing-switch designed to connect the source of supply to the armature-circuit and designed to control the slow-closing switch of the first closing solenoid, as and for the purpose set forth.
3. The combination with a motor-armature circuit and resistance therefor, of a source of supply, a reversing-switch designed to connect the source of supply to the armature-circuit, a series of solenoid-circuits each of which is provided with a slow-closing switch each except the first arranged to be actuated by the preceding solenoid and each of which switches shunts a part of the resistance, and means whereby the reversing-switch in neutral position will prevent the automatic movement of the slow-closing switch for the first solenoid-circuit and will permit the action of said slow-closing switch when the reversing-switch is actuated to connect the source of supply to the armature-circuit.
4. In a controller of the type described, a hand-operated reversing-switch arranged to connect a source of supply to the motor-armature circuit, a resistance for said armature-circuit, a series of switches designed to shunt a portion of the resistance in the armature-circuit, said switches being arranged to close automatically and provided with dashpot mechanisms, and a series of solenoids arranged to control a succeeding switch and including a rocking arm 33 operatively connected to its core and provided with a roller designed to bear against the operative element of the switch next in succession whereby to maintain it in open position the energization of each solenoid effecting the release of the roller, as and for the purpose set forth.
5. In a controller of the type described, a hand-operated reversing-switch immersed in an oil-tank and comprising a rocking segmental plate pivoted therein and provided with brushes designed for engagement with contact-plates or terminals in said tank, a resistance arranged for control by said switch, automatically-operating solenoids, and automatic circuit-closing devices for the solenoids, including a spring-drawn arm, and a dash-pot mechanism designed to retard the movement of said arm and a roller on the handle of the switch designed to contact with said arm and prevent the movement thereof whereby to hold the automatic circuit-closing device in inoperative position.
6. In a controller of the type described, the combination of a switch provided with an operating-handle, and two series of circuit-closing brushes, a series of contacts or terminals arranged between the two series of brushes, the switch being provided with a gear at its outer edge, a spring-returned pinion meshing with said gear, a circuit-closing device including a spring designed to actuate the same and a dash-pot arranged to retard the movement, and a roller carried by the handle of the switch and designed to hold the circuit-closing device in an inoperative position, as and for the purpose set forth.
7. The combination with a motor-armature circuit a source of supply therefor, a resistance, and a reversing-switch designed to connect the source of supply to the circuit of a series of solenoids arranged with automatic circuit-closing devices in series with the solenoids next in succession and each of said automatic circuit-closing devices being provided with a dash-pot mechanism, and an automatic circuit-closing device for the first of said solenoids, the same being normally held in an inoperative position by the handle of the switch and being provided with a retarding device, and means whereby the movement of said switch-handle in either direction will release the last-named circuit-closing device, as and for the purpose set forth.

In testimony whereof I affix my signature in presence of two witnesses.
